UNITED STATES PATENT OFFICE

EUGENE W. RUTHERFORD, OF NEW HAVEN, CONNECTICUT, ASSIGNOR TO THE SHOE HARDWARE COMPANY, OF WATERBURY, CONNECTICUT, A CORPORATION OF CONNECTICUT

SLIDER FOR AUTOMATIC FASTENERS

Application filed May 15, 1931. Serial No. 537,512.

My present invention relates to automatic interlocking fasteners and more particularly to an improved slider for operating the same.

The slider for operating automatic interlocking fastener members arranged in staggered relation on adjacent or aligned stringers, is usually provided with means for assisting in moving the slider along the fastener elements. This means ordinarily consists of 5 a pull tab or bail pivoted or pivoted and slidably mounted on a bail holder that is attached to one wing of the slider body. One method of attaching the bail holder to the wing of the slider body is illustrated in my 10 Patent No. 1,752,111, granted March 25, 1930. By referring to such patent, it will be seen that one end of the bail holder is securely locked to the slider body by a pair of folded lugs formed integrally with the body and the other 15 end of the bail holder is attached to the wing of the slider body by what is practically a dovetail joint. This dovetail joint is relatively difficult to make accurately and economically, special tools being required not 20 only in the formation of the dovetail portion in the wing of the slider body, but also in the manufacture of the corresponding portion on the bail holder itself. Also this type of 25 joint is relatively weak and too great a portion of the operating strain is placed on 30 the holding lugs.

My present invention is an improvement on the construction shown in my Patent No. 1,752,111, above referred to, and without limiting the invention otherwise than as required by the prior art, the same consists in a form 35 of connection between one end of the bail holder and the associated wing of the slider body. In carrying out my invention, I form 40 a rectangular slot in the desired wing of the slider body, as in former constructions, and then strike up a portion of the material of the wing adjacent one end of the rectangular slot. Such struck-up portion lies at an angle 45 to the wing of the slider body and the uppermost end of the angularly placed struck-up portion lies in a plane slightly above, but parallel to the plane in which lies the said wing. In the end of the bail holder remote from the 50 portion held in place by the lugs referred to

I form an ordinary slot of any suitable depth and of a width substantially equal to the thickness of the metal of which the body of the slider is composed. This construction is 55 relatively simple and inexpensive to make, and the holding power of this end of the bail holder is greater than the holding power of the end of the bail holder that is secured to the slider body by the pair of lugs above referred to.

The object of my invention therefore is an 60 improved slider for interlocking fastener elements.

In the accompanying drawing illustrating 65 a preferred embodiment of my invention;

Figure 1 is a plan view of a slider body before the operation of placing the wings in parallel relation to each other takes place;

Figure 2 is a plan view of a pull tab or 70 bail;

Figure 3 is a perspective view of a bail holder manufactured according to the present invention;

Figure 4 is a perspective view of a fastener slider and also a perspective view of a bail 75 holder with a pull tab or bail positioned thereon and ready to be assembled with the slider body, and

Figure 5 is a sectional side elevation of a 80 slider body with the bail holder and a bail assembled thereon.

Referring to the drawing, 10 designates a fastener slider composed of wings 11 and 12 joined together by a relatively narrow neck 13 and between the wings 11 and 12 and from either side of the neck 13 extend laterally outward lugs 14. In one of the wings, as the wing 13, is formed a rectangular slot 15 of any suitable width and length and at the end of the rectangular slot 15 remote from the neck 13 is formed a connecting element 16. This connecting element is formed by striking up the metal of the wing 12 at an angle to the body of said wing as clearly shown in the drawing and the portion of the connecting member 16 adjacent the rectangular slot 15 is struck up to a height above the surface of the wing 12 sufficient to place such end in a plane slightly above the plane in which lies the upper surface of such wing 12.

Referring to Fig. 3 there is shown a bail holder which comprises a body member 17 having extending outward from one end thereof a portion 18 that is provided on one edge with spaced ears 19. At the other end of the body 17 is formed a slot 20 that extends into the body 17 at an angle as clearly shown in Fig. 3. In the body 17 is also formed a groove 21 which acts as a bearing for the bail 22—this bail being provided with a rectangular slot 23 that enables the same to be placed in position on the body 17 as clearly shown in Fig. 4.

The structure shown in Fig. 1 is folded so as to bring the wings 11 and 12 into parallel relation with each other as shown in Fig. 4, and in this folding operation there is formed in the neck 13 a transverse groove 25 in which fits the laterally extending portion 18 from the body 17. In assembling the bail holder 17 and pull tab 24 on the slider 10, the end containing the transverse cut 20 is placed in the rectangular slot 15. The transverse slot 20 engages with the connecting element 16 and the laterally extending portion 18 is fitted into the transverse slot 25. When in this position the lugs 14 are forced in between the ears 19 on top of the portion 18, thus locking the bail holder 17 in position on the slider 10 as clearly shown in Fig. 5.

By reference to Fig. 5 it will be noted that the connection between the connector 16 and transverse slot 20 is relatively substantial in proportion to the size of the elements employed and that the holding power of the connector 16 for the bail holder 17 is relatively strong as compared with the holding power of the lugs 14 on the laterally extending portion 18 of the holder.

While I have necessarily described the preferred embodiment of my invention somewhat in detail, it is to be understood that I may vary the size, shape and proportions of the construction constituting my invention within relatively wide limits without departing from the spirit of the invention.

Having thus described my invention, what I claim and desire to protect by Letters Patent is:

1. A separable fastener slider having in combination, a pair of parallelly arranged wings spaced apart from each other, a neck member joining such wings together at one end, and having a slot extending transversely of the wings, a pair of ears formed on the neck member and adapted to be folded across the top of the slot, a holding element struck up from one wing at an angle thereto, and a bail holder having one end extending into the transversely extending slot and secured therein by said ears, and the other end having a slot into which the holding element extends.

2. A separable fastener slider having in combination a pair of parallelly arranged wings spaced apart from each other, a neck

member joining such wings together at one end, a bail holder provided at one end with a slot of a width equal at least to the thickness of the material of the wings, means on the neck member for attaching the end of the bail holder, remote from the slot, and a holding element on one of the wings struck up from the wing material and fitting into the slot in the end of the bail holder for attaching the same to the wing.

3. In a separable fastener slider, comprised of a pair of parallelly arranged wings attached together at one end, the combination with a bail holder provided at one end with a slot of a width substantially equal to the thickness of the material of the wings, of a holding element fitting into said slot and formed of a portion of the material of one of the wings bent up from the said wing and at an angle thereto.

4. In a separable fastener slider comprised of a pair of parallelly arranged wings attached together at one end, the combination with a bail holder provided at one end with a slot of a width substantially equal to the thickness of the material of the wings, of a holding element fitting into said slot and formed of a portion of the material of one of the wings, said portion being struck up from the wing to a point above the surface of such wing.

Signed at Waterbury, county of New Haven, State of Connecticut, this 11 day of May, 1931.
